DESIGN FOR A SHOE

Walter J. Devine, Harrisburg, Pa.

Application April 19, 1933. Serial No. 47,841

Term of patent 3½ years

To all whom it may concern:

Be it known that I, WALTER J. DEVINE, a citizen of the United States of America, residing at Harrisburg, in the county of Dauphin and State of Pennsylvania, have invented a new, original, and ornamental Design for a Shoe, of which the following is a specification, reference being had to the accompanying drawing forming a part thereof.

The figure illustrates a side elevation of a shoe, showing my new design.

I claim:—

The ornamental design for a shoe as shown.

WALTER J. DEVINE.
